LADING BAND ANCHORS

Orville Ingram, Toledo, Ohio, assignor to Midland-Ross Corporation, Cleveland, Ohio, a corporation of Ohio

Filed May 25, 1967, Ser. No. 641,195

10 Claims. (Cl. 105—369)

ABSTRACT OF THE DISCLOSURE

A railway freight car lading band anchor assembly adapted to be manually movable from open to closed position by rotating the anchor structure about its axis which is generally parallel to and forms a part of the load supporting floor, or containing walls of the car.

15

Background of invention

A lading band anchor of a railway freight car is adapted to secure flat high tension bands which pass over or alternately around cargo placed upon the floor of the car. The distal ends of the bands pass around the anchor unit and return the band for securement to itself. Conventionally, lading band anchors have been placed at locations to suit shipper demands and are of a type wherein an open-ended housing is placed in an area having some form of anchor design associated therewith. These types of anchors, particularly when used in flat car service have proven inadequate after a few years' service due to corrosive action of the elements, as well as the fact that they present a problem of dirt and debris collection; ice and snow immobilizing the anchor's effective use.

20

Summary of the invention

The present invention relates to a high-tension lading band anchor for railway freight cars in which an anchor is rotatably mounted to adjacent car structures and the anchor is movable from closed to open position. It is the primary object of the present invention to provide an improved lading band anchor assembly mounted on the framing member of the car and wherein the action of the housing member when moved from open to closed position causes debris and foreign matter to dislodge itself and fall free of the anchor assembly.

25

Another object of the invention is to provide a round anchor seat, a portion of which forms the trunnion for the rotatable anchor assembly.

30

An additional object of the invention is to provide a lading band anchor housing which when not in use forms a part of the floor or restraining wall of the car, thereby closing the necessary opening to receive the lading bands.

35

A further object of the invention is to provide load bearing supports for the lading bearing housing when acting as a basic car member such as the floor of a flat car.

40

A still further object of the invention is to position the housing load bearing supports so as to act as restraining walls against lateral displacement of the lading bands.

45

A feature of the invention is the elimination of fillets, either as by weldment, forging or casting, by securing the restraining walls within the housing other than at the anchor seat.

50

With the foregoing its main objectives, other objects and advantages of the invention will appear hereinafter in the detailed description, be particularly pointed out in the appended claims and illustrated in the accompanying drawings, in which:

55

FIGURE 1 is a fragmentary plan view of the loading floor of a railway flat car showing a selection of possible positioning of the invention, as well as possible selective lengths, or number of anchoring pockets per unit;

60

FIGURE 2 is an enlarged fragmentary plan view of the present invention showing the anchor housing mem-

ber in closed position and forming a load supporting portion of a railway flat car;

FIGURE 3 is a sectional view taken along lines 3—3 of FIGURE 2;

FIGURE 4 is an elevational view with a portion broken away to show in more detail the inner structure of the invention;

FIGURE 5 is an end elevational view of the anchoring device;

FIGURE 6 is a perspective view of a railway box car showing a selection of possible locations of the present invention in the floor of a box car, as well as the sides and ends of the box car.

Detailed description

Referring now in detail to the drawings, in which like reference characters designate like parts, the improved lading band anchor is designated as 12 when in open position and as 13 when in closed position as applied to the floor 14 of a railway flat car. As generally shown in FIGURE 6 is member 15 designating the floor of a railway box car, 16 the end of a box car and 17 the side of the car.

Also generally shown as 18 is a possible location of the present invention adjacent the door area and 19, as closed, in the floor of the car with 20 designating the invention in open position.

In the end of the car is shown possible locations of the invention, 21 designating a closed anchor and 22 the anchor in open position.

It will be seen that the present anchor is adaptable to application to most any location on a railway car.

Associated car structure

FLAT CAR

The side sill of a flat car is shown as 23. Connected as by riveting to side sill 23 is a crossbearer member 24. This crossbearer member 24 connects the side sill 23 to a center sill (not shown) forming a portion of the backbone of a railway car underframe. Longitudinal stringer 25 rests on crossbearer 24 and supports the car floor generally shown as 14.

BOX CAR

The end sill of a box car is shown as 26 (FIGURE 6); the center sill as 27 and the side sill as 28. As in the underframe of a flat car the box car is usually provided with a longitudinal stringer (not shown in FIGURE 6). The door post is shown as 29.

ANCHOR DETAILS

The preferred embodiment of the invention consists of a base member and is shown as 30 which is conveniently welded as at 47 to the crossbearer 24. To base member 30 is mounted upstanding bearing supports 31; bearings 32 are integral with supports 31 and are in axial alignment with the lading band anchor 33 which rotates within bearing members 22. Longitudinally spaced along anchor member 33 are housing supports 34 which act as restraining means against lateral displacement of the lading bands when the anchor is in use. When the anchor structure is in closed position and forming a portion of the floor, said housing supports act as load transmitting members. It will be noticed that supports 34 rest upon anchor 33 and have no fillets to overload the edges of the lading bands when they are drawn tightly about the anchor member 33.

Generally U-shaped housing member 36 is disposed about anchor member 33 and when in open position acts as a guide for the lading band when it is being placed around the anchor 33 for securement upon itself. The U-shaped housing member 36 is provided with end pieces

35 having an opening which surrounds anchor 33 and may be welded thereto, as well as to housing 36. Disposed between upstanding members 31 and in the path of movement of U-shaped housing is angle stop 37 which acts as a limiting means for rotation of the anchor structure.

As shown in FIGURE 3, floor 14 is provided with an additional housing stop 39 which is placed in the path of movement of housing 36. Passing through filler piece 38 is bolt 41 and nut 40 which secure stop 39 in place. Conveniently located and held in place by bolt 41 and nut 40 is a typical floor clip 50 which overlaps a portion of stringer 25 to hold the floor 14 in place. Filler 38 is provided with holes 42 so the head of the bolts 41 will be recessed below the top of the plane of the floor 14.

The outer edge of floor 14 is held in place by bolt 44 passing through side sill 23 and the bolt is held in place by washer 45 and nut 46.

The entire anchor structure is held in place and to the associated car structure as by welding 47. U-shaped housing member 36 is provided with drain holes 48, as well as a hole 49 to be used in lifting the housing member from closed position to open position.

I claim:

1. A lading band anchor for attachment to a framing member of a railway freight car comprising a substantially U-shaped housing member having end walls, said housing member rotatably mounted to a framing member and in a plane substantially parallel to and partially within the associated car structure affixed to said framing member, said housing member movable from closed position to open position, an anchoring means secured within and rotatable with said housing, the ends of said anchoring means passing through bearing means in the end walls of said housing, the said ends forming trunnion means which are adapted to be secured to upstanding members forming, in cooperation with said anchoring means, a lading band anchor structure for receiving a lading band for securement to itself, when said housing member is in open position, exposing said anchor means.

2. A lading band anchor according to claim 1, wherein bearing means is in axial alignment.

3. A lading band anchor according to claim 2, wherein

the anchor means consists of a round bar extending between and through the bearing means in the end walls.

4. A lading band anchor according to claim 3, wherein said trunnion means are rotatably mounted within spaced apart bearing members, each bearing member supported by an upstanding member affixed to a base member, a second member in cooperation with said base member retains said upstanding member in fixed relation with its counterpart.

5. A lading band anchor according to claim 4, wherein said second member, extending between said upstanding member, forms a limiting means for said rotatable U-shaped housing member.

6. A lading band anchor according to claim 1, wherein said U-shaped housing member is provided with spaced apart members acting as intermediate load-bearing supports for said housing when said lading band anchor is in closed position.

7. A lading band anchor according to claim 6, wherein said load bearing supports form, when said anchor assembly is in open position, restraining walls against lateral displacement of said lading band.

8. A lading band anchor according to claim 7, wherein said restraining walls are in embracing relationship with said anchoring means.

9. A lading band anchor according to claim 5, wherein in a portion of said U-shaped member, when in closed position, lies in a plane parallel to and forms a part of said associated car structure affixed to said framing member.

10. A lading band anchor according to claim 9, wherein said associated car structure in cooperation with a portion of said U-shaped member forms the floor of a rail-way flat car.
